UNITED STATES PATENT OFFICE

138,848

DESIGN FOR A COOKING VESSEL OR
THE LIKE

Norbert Shaeffer, Los Angeles, Calif., assignor to
Kinney Aluminum Company, Los Angeles,
Calif., a copartnership consisting of Roland T.
Kinney and Wendell H. Kinney

Application November 2, 1943, Serial No. 111,571

Term of patent 14 years

(Cl. D44—1)

To all whom it may concern:

Be it known that I, Norbert Shaeffer, a citizen of the United States, residing at Los Angeles, in the county of Los Angeles and State of California, have invented a new, original, and ornamental Design for a Cooking Vessel or the like, of which the following is a specification, reference being had to the accompanying drawing, forming a part thereof.

Fig. 1 is a side elevational view of a cooking vessel or the like, showing my new design;

Fig. 2 is an end elevational view; and

Fig. 3 is a top plan view thereof.

Fig. 4 is a vertical sectional view of the cooking vessel illustrated in Fig. 1; and

Fig. 5 is a transverse sectional view thereof.

Fig. 6 is a top plan view of the cooking vessel illustrated in Fig. 1 with the cover thereof removed.

The dominant feature of my design resides in the portion shown in full lines.

I claim:

The ornamental design for a cooking vessel or the like, as shown and described.

NORBERT SHAEFFER.
